[57] CLAIM

The ornamental design for a rod and reel case, as shown and described.

DESCRIPTION

FIG. 1 is a left side elevational view of a rod and reel case showing my new design, the opposite side being a mirror image thereof;

FIG. 2 is a top plan view thereof;

FIG. 3 is a bottom plan view thereof;

FIG. 4 is a front elevational view thereof; and

FIG. 5 is a rear elevational view thereof.

Fig. 5.
